UNITED STATES PATENT OFFICE.

ALBERT A. PAGE, OF EASTHAVEN, CONNECTICUT, ASSIGNOR TO SARGENT AND COMPANY, OF NEW HAVEN, CONNECTICUT, A CORPORATION OF CONNECTICUT.

PADLOCK.

SPECIFICATION forming part of Letters Patent No. 729,792, dated June 2, 1903.

Application filed January 30, 1901. Serial No. 45,327. (No model.)

To all whom it may concern:

Be it known that I, ALBERT A. PAGE, of the town of East Haven, county of New Haven, State of Connecticut, have invented a new and useful Improvement in Padlocks, of which the following is a full, clear, and exact description, when taken in connection with the accompanying drawings, which form a part thereof, and in which—

10 Figure 1 represents an elevation of a padlock embodying my invention; Fig. 2, a central vertical section through the same; Fig. 3, a top view of the outer shell or casing; Figs. 4 and 5, top and side views, respectively, of the inner casing or support; and Fig. 6, a side view of the hasp, in detail.

In all figures similar letters of reference represent like parts.

This invention relates to padlocks, and has 20 for its object the production of a novel, efficient, and simple padlock embodying one or more of the improvements or combinations of parts set forth and claimed hereinafter.

Referring to the drawings, the parts designated by the letter A represent the outer casing or shell, open at its lower end and provided in its upper face with two circular openings a and a'.

B represents the hasp, the two legs of which 30 are adapted to fit into the openings a and a' in the shell.

C is an inner casing or support for the cylindrical plug D and associated parts. The support C is provided at its lower end with a 35 face-plate c, adapted when the support is in place within the shell A to close the lower end of the shell. An inwardly-projecting integral flange E is located within the shell beneath the opening a, which flange is provided 40 with a slot or hole e for the screw e', adapted to be screwed into a hole c' in the support C, thus holding the support and shell together. Access to the screw e' is obviously impossible 45 while the hasp is forced home and the shorter leg thereof projects into the opening a. Within the support C, beneath the opening a' of the shell A, is a tubular socket F for the longer leg of the hasp B. Within the socket is a coiled spring f, bearing against the lower 50 end of the leg of the hasp or against a shoulder thereof, constantly tending to force the

hasp outward. An annular groove G is formed about the longer leg of the hasp, near its end, and from the upper side of the groove a portion of the inner face of the leg is cut away 55 to form a longitudinal groove g. A spring-pressed pin H fits into a socket I in the support C on the inner side of the tubular socket F. The pin H is constantly pressed outward by the spring h within the socket I. To originally insert the hasp, the pin is forced back into its socket I so that its outer end is flush with the inner wall of the tubular socket F, whereupon the longer leg of the hasp is forced inward until the pin H comes opposite to the 60 groove G or slot g, when the spring h will force it outward to engage therein and to prevent the removal of the hasp. As the pin is located on the inner side of the hasp, it is inaccessible from the outside of the casing, 70 and therefore cannot be tampered with.

As the hasp is forced home, as shown in Fig. 2, the pin H moves along the longitudinal slot g, but when the hasp is forced outward by the spring f the pin H travels along 75 the slot g in the opposite direction and permits the hasp to be turned while it engages in the annular groove G.

The cylindrical plug D is held in place by means of a washer K at its inner end, which 80 end is also provided with a bit M, having two engaging ends m and m', adapted to engage in the slots N and n in the two legs of the hasp, thus making a double engagement therewith.

A washer O secures the bit M to the plug D by means of screws o, Fig. 4. The plug is provided with the usual tumblers P and the usual tumbler-bolts Q, sliding in suitable sockets q within the support C. Within 90 the sockets q are also located springs R for operating the tumbler-bolts in well-known manner. A spring S tends to keep the bit M in its normal position.

Having now described my invention, which may vary somewhat in its details without departing from the spirit thereof, what I claim, and desire to secure by Letters Patent, is—

1. In a padlock, the combination with a hasp; of a casing or shell having hasp-openings at one end; a support adapted to be inserted in said casing at the end thereof oppo-

site said hasp-openings; a socket in said support registering with one of said hasp-openings, and in which one leg of said hasp is adapted to be permanently secured; an engagement between said shell and said support located within said shell and accessible through the other hasp-opening while said leg of said hasp is secured in the socket of said support, but inaccessible when both legs of said hasp are locked in said support; and means for locking said hasp to said support, substantially as described.

2. In a padlock, the combination with a hasp; of a casing or shell having hasp-openings at one end and an opening for a support in the opposite end; a separate support adapted to be inserted in said casing at the end opposite said hasp-openings; a socket in said support registering with one of said

hasp-openings, and in which one leg of said hasp is adapted to be permanently secured; and means for locking both legs of said hasp to said support, substantially as described.

3. In a padlock, the combination with a hasp; of a support for said hasp; a socket in said support for one leg of said hasp; a pin projecting into said socket to engage said hasp to permit it limited longitudinal and free rotary movement; and a spring yieldingly holding said pin in such engagement, substantially as described.

In witness whereof I have hereunto set my hand this 24th day of January, 1901.

ALBERT A. PAGE.
